INVENTOR:

W. A. Morse

UNITED STATES PATENT OFFICE.

WILLIAM A. MORSE, OF PHILADELPHIA, PENNSYLVANIA.

IMPROVEMENT IN LEAD-PENCILS.

Specification forming part of Letters Patent No. 134,215, dated December 24, 1872.

To all whom it may concern:

Be it known that I, WILLIAM A. MORSE, of the city and county of Philadelphia and State of Pennsylvania, have invented certain Improvements in Lead-Pencils, of which the following is a specification:

My improvement and invention consist in providing a common rubber head, now in general use on wood pencils, with a fibrous or suitable material for cleaning paper after erasing lead-marks.

In the accompanying drawing, Figure 1 is a perspective view of my improved erasing and cleaning head attached to a pencil.

W is a rubber head, which may be of the form now common in use. A is the paper-cleaner, which I prefer to make of soft cloth or felt, but any material may be used that is best adapted to clean paper; nor do I wish to confine myself to any particular form or style of cleaner, as different-formed rubber heads may require differently-constructed paper-cleaners to attach thereto.

I attach the cleaner to the rubber head by means of glue or strong gum.

I prefer to use a metallic spring tube to attach the above to a pencil, but paper-tubing, in connection with the cloth wiper or cleaner, may be used instead of metal; or it may be attached without any connecting-tube.

The merit of my improvement and its advantage will be readily understood, as all have experienced the difficulty of cleaning paper of the dirt which always accumulates under a rubber eraser in erasing pencil-marks from paper.

Its object is to do away with this annoyance, and will be readily understood without further description.

What I claim as my invention is—

A paper-cleaner, substantially as described, in combination with a rubber eraser adapted to a pencil, as set forth.
